UNITED STATES PATENT OFFICE.

RALPH SHIPMAN, OF SUNBURY, PENNSYLVANIA.

CARBURETER.

1,222,688.

Specification of Letters Patent. Patented Apr. 17, 1917.

Application filed July 22, 1911. Serial No. 640,032.

To all whom it may concern:

Be it known that I, RALPH SHIPMAN, a citizen of the United States, residing at Sunbury, in the county of Northumberland and State of Pennsylvania, have invented 5 certain new and useful Improvements in Carbureters, of which the following is a specification.

This invention relates to improvements in carbureters for explosive engines whereby the complete vaporization of the liquid fuel is insured and whereby the proportions of liquid fuel to air and the quantity of gaseous mixture may be automatically controlled according to the demands of the engine. The construction and operation of the invention will be clear from the following description, taken in connection with the accompanying drawing, in which,

20 Figure 1 is a vertical section through the carbureter taken on the line 1—1 of Fig. 4;

Fig. 2 is a top plan view of the same with the upper portion of the casing removed;

Fig. 3 is a sectional view, taken through 25 the atomizer,

Fig. 4 is a section on the line 4—4 of Fig. 1, the float being omitted, and,

Fig. 5 is a detail view showing a modified form of baffle.

30 Referring to the drawing, A indicates the casing of the carbureter, comprising the parts 1 and 2, secured together by screws α , and 4 indicates an air inlet pipe detachably secured to the part 2. The part 1 is suited 35 for attachment to the intake pipe of a hydrocarbon engine and a throttle valve 5, of the butterfly type, is arranged in the part 1, upon a rod 6, to which is secured a lever 7, by means of which the position of the 40 throttle valve may be controlled. Within the part 1, below the throttle valve, is also arranged an inclined baffle 8, preferably of wire gauze, and corrugated, as shown in the drawing. This wire gauze extends nearly 45 or quite across the interior of the part 1 and beneath its upper end a pocket 9 is arranged in the casing for a purpose hereinafter explained. The part 1 communicates with the upper part 2 through an opening 3 in the 50 lower end of the part 1 and the baffle 8 projects over this opening.

The part 2 of the casing has an air passageway a extending vertically through it, said passageway connecting at its upper end 55 with the interior of the part 1, and at its lower end with the air inlet pipe 4. Within

this passageway is arranged a draft-controlled valve 12, which is mounted upon a rocker 13, the latter, in turn, being pivoted upon a transverse rod 14. This valve is 60 normally held in an inclined position by a spring 15, the connections of which are hereinafter described, and the upper portion of the valve rests against a partition plate 16 which forms a stop for the valve. By this 65 arrangement the greater portion of the passageway a is normally closed by the valve, which extends diagonally across the passageway to said stop or partition, as shown in full lines in Fig. 1 of the drawing. The 70 valve 12 does not, however, cut off the entire air supply, when closed, as an auxiliary air passageway a' is provided through which a current of air may flow past the atomizer B. As shown in the drawing, this auxiliary 75 passageway is formed by the partition 16 and the curved wall or partition 17 which extends through the part 2 and forms one wall of the fuel reservoir 10 as well as a wall of the air conduit or passageway. This 80 wall 17 has an opening 18 through which the liquid fuel may flow from the reservoir into a vertically arranged fuel nozzle b which latter nozzle is surrounded by an air nozzle b' , the latter being arranged to slide upon 85 the lower part of the nozzle b . As shown in the drawing, the upper portion of the fuel nozzle is of smaller diameter than the base, in order to provide an air passageway between the two nozzles, and small perforations 19 are arranged in the air nozzle b' below the top of the fuel nozzle. The air nozzle extends a short distance above the end of the fuel nozzle and the upper end of the air nozzle is contracted, as shown at 19^a, 90 so that its internal diameter, at the outlet opening 19^b, is less than elsewhere. Secured 95 to the part 1, above the atomizer, is a vertically adjustable pin 20 which projects slightly into the opening in the upper end of 100 the air nozzle and this pin tapers upwardly, as shown in Fig. 3. The air nozzle is movable vertically relatively to the fuel nozzle and to this tapering pin, and it will be seen that if the air nozzle is moved its full distance upwardly, as indicated in dotted lines 105 in Fig. 1, the area of the opening 19^b between the tip of the air nozzle and the pin 20 will be larger than when the air nozzle is in its normal position. This is not true of the 110 initial movement of the nozzle b' as, for reasons hereinafter stated, the pin 20 is so

formed at its lower end and so related to the opening in the nozzle, that during the initial movement of the nozzle, the area of the opening will not enlarge, but a continued upward movement of the nozzle will cause such enlargement.

This nozzle b' is so connected to the valve 12 that when the latter opens, owing to the suction of the engine, it will lift the nozzle b' , and when the draft through the carbureter is so slight that the valve 12 will not lift, the nozzle b' will remain in normal position. In order to accomplish this automatic movement of the nozzle, the latter is connected by links 22, to a cross bar 23, which rests in notches 24 in a forked arm 13^a of the rocker 13, and this cross piece 23 is connected by a spring 15 to a bracket 26, secured to the casing. The spring 15 holds the cross piece 23 against the bottom of the notches in the rocker, preventing lost motion between the links and the rocker, and the spring also holds the valve 12 normally in closed position.

A needle valve 27 is provided for controlling the flow of gasoline from the reservoir to the fuel nozzle b and a float 28 is arranged in the reservoir and provided with arms 29 which are pivoted upon pins 30. To one of these arms is secured a valve rod 31 having at its end a valve 32 arranged within a tubular fitting 33 through which the liquid fuel may flow from a fitting 34 connected to the source of supply. The float and its connected valve operate in the usual way to maintain the fuel in the reservoir at a practically constant level.

The air pipe 4, as shown in the drawing, is connected to the lower end of the carbureter casing by a bolt 35 suspended from a cross rod 36 which passes through the air conduit or passageway of the casing. The inlet pipe may be turned about the bolt 35, as an axis, so as to take any desired position relatively to the carbureter casing, and it is clamped to the casing by means of a nut 37 upon the bolt.

The operation of the carbureter is as follows: When the throttle valve 5 is only open slightly, the draft through the carbureter is, of course, slight and under such conditions the spring 15 holds the main air valve 12 closed. The air passing through the carbureter must then flow through the auxiliary air passageway a' and upwardly around the atomizer B, thence to the space between the atomizer and the throttle valve, which is the mixing chamber of the device. The air flowing around the sides of the air nozzle b' , and also through the perforations 19 and opening 19^b, will cause a sufficient amount of the liquid fuel to flow from the nozzle b to saturate the air and operate the engine. If the partition 16 were omitted, the valve 12 would cause the air current to flow around

the atomizer and a satisfactory mixture of the air and liquid fuel would result, but it happens, with devices of this kind, that bubbles and drops of gasoline will sometimes issue from the fuel nozzle and drop downwardly without becoming vaporized. In order to vaporize such stray bubbles and drops of the liquid, I arrange the partition 16 so as to provide a restricted air passageway a' around and below the atomizer through which the air flows at sufficient speed to support and vaporize any drops or bubbles falling from the vaporizer. The mixture passes from the atomizer through the opening 3 and against the baffle 8 and any drops or bubbles which are not vaporized, or broken on the baffle 8, will drop into the pocket 9. The liquid accumulating in the pocket 9 will slowly vaporize during the operation of the engine.

When the throttle valve 5 is opened to cause the engine to take a greater supply of mixture, the increased suction of the engine causes the valve 12 to open partly, or to the full extent, as shown in dotted lines in Fig. 1, and this opening movement of the valve 12 causes the air nozzle b' to move upwardly, as indicated in dotted lines, the area of the opening 19^b being thus enlarged to permit a greater quantity of liquid fuel to flow out and combine with the greater volume of air flowing through the conduit. Thus it will be seen that by properly proportioning the pin 20 and the relative movement of the parts, the quality and volume of the mixture best adapted for the demands of the engine may be automatically maintained.

If the draft controlled valve 12 is closed and the engine is working with the throttle valve only slightly open, and the latter is then thrown wide open, a strong draft is created through the carbureter. Owing to the inertia of the valve 12 and the parts connected therewith a certain amount of time is required for the valve to move from its closed to its open position, and during this time the increased suction would cause the fuel to spurt from the nozzle b in excess of the amount required for the volume of air flowing during the interval while the valve 12 is opening. To prevent this excess flow of gasoline while the inertia of the valve, and its connected parts, is being overcome, the lower end 20^a of the pin is so formed and related to the opening 19^b that during the initial upward movement of the air nozzle b' the area of the opening 19^b will not be increased, or the pin and said opening may be so formed and related as to cause the area of the opening to be slightly decreased during this initial movement; but as hereinbefore stated, when the valve 12 opens further the area of the opening 19^b is increased by reason of the form and relation of the pin and the circumference of the opening.

The form and relation of the pin and the opening in the air nozzle will vary somewhat according to the cylinder dimensions of the particular engine to which the carbureter 5 may be applied and they may also be varied to vary the proportions of mixture required under different working conditions. I do not therefore restrict myself to any exact form of pin or nozzle.

10 The corrugated baffle in the carbureting chamber may be made as indicated in Fig. 5, wherein 8^a indicates a fabric of wire gauze, having the upper bends 8^b clogged or filled with solder so as to prevent the mixture from flowing directly through and cause it to take a tortuous course through the sides of the folds.

What I claim is:—

1. In a carbureter for explosive engines, 20 a casing, having an air passageway there-through, a fuel nozzle therein, a draft op-erated valve and means controlled thereby for first damping and then increasing the flow of air past the end of the nozzle as the valve moves from its closed to its open position.

2. In a carbureter for explosive engines, a casing having an air passageway there-through, fuel and air nozzles in said pas-sageway, the air nozzle surrounding the fuel nozzle and having a vent, a pin of varying cross-sectional area in line with said vent, and a draft-controlled valve adapted to move said air nozzle and pin relatively 35 to one another, said pin being formed so as to first decrease and then increase the size of the vent as the valve moves from its closed to its open position.

3. In a carbureter for explosive engines, 40 a casing having an air passageway there-through, fuel and air nozzles in said pas-sageway, the air nozzles surrounding the fuel nozzle and having a vent, a pin in line with said vent, said pin having oppositely

tapered portions, and a draft-controlled 45 valve adapted to move said pin and air nozzle relatively to one another to cause the pin to enter the vent.

4. In a carbureter for explosive engines, 50 a casing having an air passageway extend-ing vertically therein, air and fuel nozzles arranged vertically in said passageway, said air nozzle surrounding the fuel nozzle and having an air inlet below the vent of the fuel nozzle and a vent above the top of the latter 55 nozzle, a draft-actuated valve, and means co-acting therewith for first damping and then increasing the flow of fluid through the air nozzle as the valve moves from closed to open position.

5. In a carbureter for explosive engines, 60 a casing having an air passageway there-through, vertically arranged air and fuel nozzles in said passageway, said air nozzles surrounding the fuel nozzle and said air 65 nozzle having a vent in its upper end, a stationary pin in line with said vent, and a draft-controlled valve connected to said air nozzle and adapted to move the same longi-tudinally of the pin, said pin being formed 70 so as to first decrease and then increase the size of the vent as the valve moves from its closed to its open position.

6. In a carbureter for explosive engines, 75 a casing having a mixing chamber in its up-er portion and having a main passageway and an auxiliary vertically arranged air passageway leading to said chamber, and an atomizer comprising a fuel nozzle and a surrounding air nozzle arranged in the up-80 per part of said auxiliary air passageway adjacent the mixing chamber.

In testimony whereof I affix my signature, in presence of two witnesses.

RALPH SHIPMAN.

Correction in Letters Patent No. 1,222,688.

It is hereby certified that in Letters Patent No. 1,222,688, granted April 17, 1917, upon the application of Ralph Shipman, of Sunbury, Pennsylvania, for an improvement in "Carburetors," an error appears in the printed specification requiring correction as follows: Page 3, line 42, claim 3, for the word "nozzles" read nozzle; and that the said Letters Patent should be read with this correction therein that the same may conform to the record of the case in the Patent Office.

Signed and sealed this 1st day of May, A. D., 1917.
